(57) CLAIM

I claim the ornamental design for a carrying case, as shown and described.

DESCRIPTION

FIG. 1 is a perspective view of a carrying case;

FIG. 2 is a front view of FIG. 1;

FIG. 3 is a rear view of FIG. 1.;

FIG. 4 is a left side view of FIG. 2; and,

FIG. 5 is a right side view of FIG. 2.

1 Claim, 5 Drawing Sheets
